MOTOR CONTROLLER

Paisley B. Harwood, Milwaukee, and John M. Newman, Wauwatosa, Wis., assignors to Cutler-Hammer, Inc., Milwaukee, Wis., a corporation of Delaware

Application November 18, 1939, Serial No. 305,098

9 Claims. (Cl. 172—288)

This invention relates to motor control systems, and while not limited thereto is particularly applicable to systems of control for motor driven machine tools such as wire drawing machines of the multiple unit type.

Wire drawing machines of the multiple unit type are usually provided with a plurality of reducing dies each of which has a pulling drum associated therewith. The several drums are driven by a single motor and the wire is wrapped around said drums for successive drawing through the reducing dies.

In preparing such machines for a drawing operation the operator threads the wire through the first reducing die and then operates the motor for a short period to effect winding of a few turns of the wire upon the first pulling drum. The wire is then threaded through the second reducing die and the motor is again operated for a short period to effect winding of a few turns of the wire upon the second pulling drum. This process is repeated until the wire is successively threaded through all of the reducing dies and wound upon their associated pulling drums.

During these operations it is necessary to operate the motor at a relatively low speed, and in practice it has been found that a period of approximately 4 seconds must be allowed for each of the winding operations.

It has heretofore been proposed to control wire drawing machines of the multiple unit type by means of a time limit controller including a plurality of accelerating switches which operate to shunt a starting resistance for the driving motor in steps separated by given time intervals. However, such controllers have been found objectionable for the following reason. During preparation of the machine for a drawing operation the load on the driving motor is increased each time

the wire is threaded through a die and wound upon the pulling drum associated therewith. The accelerating switches of a controller of the aforesaid type may be set to operate successively at 4 seconds intervals so that regardless of varying load conditions the motor will operate at a relatively low speed for the required interval during each of the winding operations. However, when the wire is to be wound upon the second drum or possibly the third drum the driving

motor may not have sufficient torque to start until after the first accelerating contactor closes. It is, therefore, necessary for the operator to wait at least 4 seconds before the winding operation is started, and if sufficient torque is not developed for starting until the second accelerating con-

tactor closes it is necessary to wait 8 seconds. Obviously such periods of delay before the motor is started are undesirable, and the present invention has among its objects to provide an improved controller which overcomes this objection.

Another object is to provide an accelerating controller for motor driven machines of the aforesaid type which operates at an extremely rapid accelerating rate until the motor starts and thereafter operates at a reduced accelerating rate to bring the motor up to running speed.

Various other objects and advantages of the invention will hereinafter appear.

The accompanying drawings illustrate an embodiment of the invention which will now be described, it being understood that various modifications may be made in the embodiment illustrated without departing from the spirit and scope of the appended claims.

In the drawings,

Figure 1 is a straight line diagrammatic representation of a control system embodying the invention, and

Fig. 2 is a key illustration of the switches and relays embodied in Fig. 1.

The illustration of the switches and relays in Fig. 2 shows them with their coils and contact members disposed in horizontal alignment with their positions in the straight line circuits of Fig. 1 so that the reader may readily determine the position of the coil and contact members of any switch or relay in the straight line circuit. The reference characters also serve as a guide to the relation between the operating coils of the switches and relays and their associated contacts. For example in switch 1M the operating coil 1M¹ operates contacts 1M², 1M³ and 1M⁴.

The switches and relays are named as follows:

1M	Main switches	40
2M		
1A	Accelerating switches	45
2A		
3A	Voltage relays	50
4A		
5A		
1VR	AS Armature shunt switch DB Dynamic braking switch FA Field accelerating switch CT Timing relay UV Undervoltage relay	
2VR		
3VR		

Referring to Fig. 1, the same illustrates a direct

current motor M to be supplied with current from a direct current supply circuit indicated by lines L¹, L². The motor shown is provided with an armature A, a series field winding F¹, and a shunt field winding F².

The control means for motor M includes a pair of electromagnetically operated main switches 1M and 2M for connecting armature A, and series field winding F¹ across lines L¹, L² in series with a plurality of starting resistance sections R¹ to R⁵, inclusive. The control means for said motor also includes a plurality of electromagnetically operated accelerating switches 1A to 5A for successively shunting resistance sections R¹ to R⁵; a field accelerating switch FA for controlling accelerating resistance sections R⁷ and R⁸ in the shunt field circuit of said motor, and a dynamic braking switch DB for connecting a dynamic braking resistance R⁹ in shunt with armature A.

The main switches 1M and 2M and also the accelerating switches 1A to 5A, inclusive, are of a conventional type, said main switches each having an operating winding M¹ and said accelerating switches each having an operating winding A¹ and a holding winding A². The operating windings of main switches 1M and 2M and also the operating windings of accelerating switches 1A to 5A are controlled by a master switch MS having stationary contacts 1, 2, 3 and 4 and co-operating movable contacts 1^a, 2^a, 3^a and 4^a. Response of the accelerating switches 1A, 2A, and 3A is timed by capacitors C¹, C² and C³, respectively, and also by voltage relays 1VR, 2VR and 3VR, respectively. Capacitor C¹ and a resistance r¹ are connected in parallel with the holding coil 1A² of accelerating switch 1A; capacitor C² and a resistance r² are connected in parallel with the holding coil 2A² of accelerating switch 2A, and capacitor C³ and a resistance r³ are connected in parallel with the holding coil 3A² of accelerating switch 3A. Voltage relay 1VR is provided with a set of normally closed contacts 1VR² for connecting a resistance r⁴ in shunt with the holding coil 1A² of accelerating switch 1A; voltage relay 2VR is provided with a set of normally closed contacts 2VR² for connecting a resistance r⁵ in parallel with the holding coil 2A² of accelerating switch 2A, and voltage relay 3VR is provided with normally closed contacts 3VR² for connecting a resistance r⁶ in parallel with the holding coil 3A² of accelerating switch 3A. The operating windings 1VR¹, 2VR¹ and 3VR¹ of said voltage relays are connected in parallel with each other and with a resistance section R⁶, and the armature shunt switch AS provides for connection of said winding and said resistance across the terminals of armature A.

Accelerating switches 4A and 5A are rendered operative upon response of the dynamic braking switch DB. Relay CT controls the dynamic braking switch DB and the armature shunt switch AS and said relay is provided with timing control means including a capacitor C⁴ which is connected across the terminals of operating winding CT¹ through the medium of a resistance r⁷. Field accelerating switch FA is controlled by accelerating switch 5A and operation thereof is timed by a capacitor C⁵ which is connected across the terminals of operating winding FA¹ through the medium of a resistance r⁸.

The controller also includes stop push buttons 5 and 6 which are connected in series in the energizing circuit of undervoltage relay UV and as hereinafter set forth said relay when deenergized necessitates return of master switch MS to

off position as a prerequisite for restarting of the motor.

The operation of the aforescribed controller and the circuit connections thereof will now be more fully described.

With voltage on lines L¹, L² and master switch MS in off position, under voltage relay UV is energized by a circuit extending from line L¹ through contacts 1, 1^a, 2^a and 2 of master switch MS through the operating winding UV¹ of said relay and through stop push buttons 5 and 6 to line L². Upon response of the under voltage relay UV the contacts UV² thereof shunt master switch MS to establish a maintaining circuit for the operating winding UV¹ of said relay.

Also with voltage on lines L¹, L² the holding windings associated with accelerating switches 1A to 5A and the operating windings associated with field accelerating switch FA and timing relay CT are energized as follows. Holding winding 1A² of accelerating switch 1A is energized through the medium of contacts 1M⁴ of main switch 1M and the capacitor C¹ associated therewith is charged through the medium of resistance r¹. Holding winding 2A² of accelerating switch 2A is energized through the medium of contacts 1A⁴ of accelerating switch 1A and the capacitor C² associated therewith is charged through the medium of resistance r². Holding winding 3A² of accelerating switch 3A is energized through the medium of contacts 2A⁴ of accelerating switch 2A and the capacitor C³ associated therewith is charged through the medium of resistance r³. Holding windings 4A² and 5A² of accelerating switches 4A and 5A are connected in series and are energized through the medium of a resistance r⁹. Operating winding FA¹ of field accelerating switch FA is energized through the medium of contacts 5A⁴ of accelerating switch 5A and the capacitor C⁵ associated therewith is charged through the medium of resistance r⁸. Operating winding CT¹ of timing relay CT is energized through the medium of contacts 3A⁴ of accelerating switch 3A and the capacitor C⁴ associated therewith is charged through the medium of resistance r⁷.

Upon energization of field accelerating switch FA contacts FA² and FA³ close, and upon closure of contacts FA² resistance sections R⁷ and R⁸ are shunted to provide for connection of shunt field winding F² directly across lines L¹, L². Upon energization of timing relay CT the contacts CT² thereof open to interrupt a shunt circuit around the operating winding AS¹ of armature shunt switch AS and the contacts CT³ thereof open to prevent energization of the dynamic braking switch DB.

To effect starting of the motor, master switch MS is moved into its on position. The operating windings 1M¹ and 2M¹ of main switches 1M and 2M are then energized by a circuit extending from line L¹ through contacts UV² of under voltage relay UV through contacts 2, 2^a, 3^a and 3 of said master switch, through the operating windings of said main switches and through contacts UV³ of said under voltage relay to line L². Upon response of main switches 1M and 2M armature A and series field windings F¹ are connected across lines L¹, L² through the medium of resistance sections R¹ to R⁵, inclusive. Also the shunt field winding F² is connected directly across lines L¹, L² by contacts FA² of field accelerating switch FA and resistance section R⁹ is connected across the motor armature A by the dynamic braking switch contacts DB².

Immediately upon response of main switches 1M and 2M the operating windings 1A¹, 2A¹ and 3A¹ of accelerating switches 1A, 2A and 3A are energized by a circuit extending from line L¹ through contacts UV² of under voltage relay UV through contacts 2, 2^a, 4^a and 4 of the master switch MS to and through said operating windings and through contacts 1M³ and 2M³ of said main switches to line L². However, accelerating switches 1A, 2A and 3A do not respond immediately due to the action of their associated holding windings A². Also upon response of main switches 1M and 2M the operating winding AS¹ of armature shunt switch AS is connected across lines L¹, L² through the medium of contacts 1M³ and 2M³ of said main switches. The armature shunt switch AS thus responds immediately upon closure of main switches 1M and 2M and the contacts AS² thereof connect resistance r⁶ and the operating windings 1VR¹, 2VR¹ and 3VR¹ of the voltage relays across the terminals of armature A to render said voltage relays responsive to given counter-voltage values in the motor circuit.

Upon response of main switch 1M the contacts 1M⁴ thereof interrupt the energizing circuit for the holding winding 1A² of accelerating switch 1A. Assuming that the motor starts upon closure of main switches 1M and 2M the countervoltage in the motor circuit effects response of relay 1VR² and upon response of said relay the contacts 1VR² thereof interrupt the shunt circuit around the holding winding 1A² including resistance r⁴. Holding winding 1A² is thus subjected to the discharge of capacitor C¹ and after a predetermined prolonged period of delay the voltage in said winding is reduced to a value to permit response of accelerating switch 1A under the action of its operating winding 1A¹. However, assuming that the load on the motor is such that the same fails to start immediately after closure of main switches 1M and 2M voltage relay 1VR remains in circuit closing position to provide for discharge of the energy in holding winding 1A² and capacitor C¹ in a relatively short interval through resistance R⁴. The holding effect of winding 1A² is thus quickly reduced to permit operation of accelerating switch 1A under the action of its operating winding 1A¹ after a relatively short interval upon closure of main switches 1M and 2M. Response of accelerating switch 1A excludes resistance section R¹ from the armature circuit of the motor.

Upon response of accelerating switch 1A the contacts 1A⁴ thereof interrupt the energizing circuit for the holding winding 2A² of accelerating switch 2A, and assuming that the motor starts upon exclusion of resistance section R¹ the counter-voltage in the motor circuit effects response of voltage relay 2VR. Holding winding 2A² is then subjected to the discharge of capacitor C² and after a prolonged period of delay the voltage in said holding winding is reduced to a value to permit operation of accelerating switch 2A under the action of its operating winding 2A¹. However, if the load on the motor is such that the same fails to start upon exclusion of resistance section R¹, voltage relay 2VR remains in circuit closing position to provide for discharge of the energy in holding winding 2A² and capacitor C² in a relatively short interval through resistance R⁵. Thus if the motor fails to start upon response of accelerating switch 1A, accelerating switch 2A responds after a relatively short interval under the action of its operating winding 2A¹ and the contacts 2A³ thereof shunt resistance section R².

Immediately upon response of accelerating switch 2A the contacts 2A⁴ interrupt the energizing circuit for the holding winding 3A² of accelerating switch 3A. Assuming that the motor starts upon exclusion of resistance section R² the counter-voltage in the motor circuit effects response of voltage relay 3VR. Holding winding 3A² is then subjected to the discharge of capacitor C³ and after a prolonged period of delay the voltage in said holding winding is reduced to a value to permit response of accelerating switch 3A under the action of its operating winding 3A¹. If the load on the motor is such that the same fails to start upon exclusion of resistance section R² voltage relay 3VR remains in closed position to provide for discharge of the energy in holding winding 3A² and capacitor C³ in a relatively short interval through resistance r⁶. Thus if the motor fails to start upon response of accelerating switch 2A, accelerating switch 3A responds after a relatively short interval under the action of its operating winding 3A¹ and the contacts 3A³ thereof shunt resistance section R³.

Upon response of accelerating switch 3A the contacts 3A⁴ thereof open to disconnect the operating winding CT¹ of timing switch CT from lines L¹, L². Operating winding CT¹ is then subjected to the discharge of capacitor C⁴ and after a predetermined interval the voltage of said winding is reduced to a value to permit opening of said timing relay. Upon opening of timing relay CT the contacts CT² thereof close prior to contacts CT³ and shunt the operating winding AS¹ of armature shunt switch AS. Contacts AS² are thus opened to deenergize the operating windings 1VR¹, 2VR¹ and 3VR¹ of the voltage relays and to exclude resistance R⁶. Also upon dropping out of timing relay CT the contacts CT³ thereof connect the operating winding DB¹ of dynamic braking switch DB across lines L¹, L² through the medium of contacts 1M³ and 2M³ of the main switches 1M and 2M.

Dynamic braking switch DB then responds to open its contacts DB² and close its contacts DB³ and DB⁴. Contacts DB² in opening interrupt the shunt circuit around armature A including resistance R⁹. Contacts DB³ in closing establish an energizing circuit for the operating windings of accelerating switches 4A and 5A, said energizing circuit extending from line L¹ through contacts UV² of relay UV through contacts 2, 2^a, 4^a and 4 of master switch MS to and through the operating windings 4A¹ and 5A¹ of said accelerating switches and through contacts 1M³ and 2M³ of the main switches to line L². Contacts DB⁴ in closing shunt the holding winding 4A² of accelerating switch 4A to permit response of said switch under the action of its operating winding 4A¹. Thus upon response of accelerating switch 4A, resistances R⁶, R⁹ and R⁴ are excluded from the motor circuit to effect a further step of acceleration of the motor.

Upon response of accelerating switch 4A the contacts 4A⁴ thereof shunt the holding winding 5A² to provide for response of accelerating switch 5A under the action of its operating winding 5A¹. Upon response of accelerating switch 5A the contacts 5A³ thereof shunt accelerating resistance section r⁵. Also upon response of accelerating switch 5A the contacts 5A⁴ thereof interrupt the energizing circuit for field accelerating switch FA, and the operating winding FA¹ of said switch is then subjected to the discharge of capacitor C⁵ to delay opening of said switch. After a predetermined interval contacts FA² open 75

to connect resistances R^7 and R^8 in parallel in the energizing circuit of shunt field winding F^2 , and thereafter contacts FA^3 open to exclude resistance section R^7 from said circuit. Accelerating switch FA thus operates after a predetermined period of delay upon response of accelerating switch $5A$ to provide two steps of acceleration by weakening of the shunt field winding F^2 .

The motor may be stopped at any time during acceleration or after the same is brought up to full running speed by momentary depression of either of the push buttons 5 or 6. Depression of either of said push buttons interrupts the afore-described maintaining circuit for the operating winding UV^1 of under voltage relay UV , and said relay then drops out to open its associated contacts UV^2 and UV^3 . Upon opening of these contacts the energizing circuits for operating coils of main switches $1M$ and $2M$, accelerating switches $1A$ to $5A$ and dynamic braking switch DB are all interrupted for return of said switches to normal position. Field accelerating switch FA is then energized through the medium of contacts $5A^4$ of accelerating switch $5A$ to provide for exclusion of resistance sections R^7 and R^8 in the energizing circuit of shunt field winding F^2 and resistance section R^9 is connected across the terminals of armature A by contacts DB^2 of the dynamic braking switch DB . The motor is thus dynamically braked to effect quick stopping thereof. As is apparent, upon dropping out of under voltage relay UV the master switch MS must be returned to off position as a prerequisite to restarting of the motor.

In connection with the foregoing it should be noted that the above described controller is particularly adapted for use in connection with motor driven wire drawing machines and meets requirements hereinbefore discussed. In other words, resistances R^1 and R^3 are proportioned to effect starting of the driving motor under all load conditions, and upon starting of the motor the controller insures slow speed operation thereof for a sufficient time to effect the winding operations hereinbefore discussed.

What we claim as new and desire to secure by Letters Patent is:

1. In a motor controller, in combination, a plurality of starting resistances in the motor circuit, a plurality of electromagnetic accelerating switches each for shunting one of said resistances, means for controlling said switches to effect operation thereof sequentially, and means associated with said former means for timing the operation of said switches to effect exclusion of said resistances from the motor circuit at a rapid rate until the motor starts and to thereafter effect exclusion of resistances remaining in the motor circuit at a reduced rate to bring the motor up to running speed.

2. In a motor controller, in combination, a plurality of starting resistances in the motor circuit, a plurality of electromagnetic accelerating switches each for shunting one of said resistances, each of said switches having an operating winding and a holding winding associated therewith, means for controlling said windings to provide for operation of said switches in a given sequence, and means associated with said holding windings for timing the operation of said switches to provide for exclusion of said resistances from the motor circuit at a rapid rate until the motor starts and to thereafter effect exclusion of resistances remaining in the motor circuit at a reduced rate to bring the motor up to running speed.

3. In a motor controller, in combination, a plurality of electromagnetic accelerating switches each having a capacitor associated therewith for delaying operation thereof, control means for effecting operation of said accelerating switches in a given sequence subject to delay by said capacitors, and means for modifying the delaying effect of said capacitors upon given electrical conditions in the motor circuit.

4. In a motor controller, in combination, a plurality of electromagnetic accelerating switches each having a capacitor associated therewith for delaying operation thereof, control means for effecting operation of said accelerating switches in a given sequence subject to delay by said capacitors and means subjected to control by the counter-voltage in the motor circuit for modifying the delaying effect of said capacitors.

5. In a motor controller, in combination, a plurality of electromagnetic accelerating switches each having a capacitor associated therewith for delaying operation thereof, control means for effecting operation of said accelerating switches in a given sequence subject to delay by said capacitors, and a plurality of relays subjected to control by the counter-voltage in the motor circuit, each of said relays being associated with one of said capacitors to modify the delaying effect thereof.

6. In a motor controller, in combination, a plurality of starting resistances in the motor circuit, a plurality of electromagnetic switches each for shunting one of said resistances, each of said switches having an operating winding and a holding winding associated therewith, a normally closed energizing circuit for each of said holding windings, means acting upon establishment of power connections for the motor to energize said operating windings and to successively interrupt the energizing circuits of said holding windings for successive operation of said switches, a capacitor associated with each of said holding windings and coating therewith upon interruption of its associated energizing circuit to delay operation of its associated switch, and means subjected to control by the counter-voltage of the motor for modifying the delaying effect of said capacitors.

7. In a motor controller, in combination, a plurality of electromagnetic accelerating switches each having a device associated therewith for delaying operation thereof, control means for effecting operation of said accelerating switches in a given sequence subject to delay by their associated delaying devices, and means associated with at least the first switch of said sequence for normally reducing the delaying effect of its associated delaying device, said latter means being rendered ineffective upon starting of the motor.

8. In a motor controller, in combination, a plurality of electromagnetic accelerating switches each having a device associated therewith for delaying operation thereof for a predetermined interval, control means for effecting operation of said accelerating switches in a given sequence subject to delay by their associated delaying devices, and a plurality of relays each associated with one of said switches and acting to normally reduce the delaying effect of the device associated therewith, each of said relays being responsive upon starting of the motor to subject its respective switch to the full delaying effect of the device associated therewith.

9. In a motor controller, in combination, a plurality of starting resistances in the motor cir-

cuit, a plurality of electromagnetic switches each for shunting one of said resistances, each of said switches having an operating winding and a holding winding associated therewith, a normally closed energizing circuit for each of said holding windings, means acting upon establishment of power connections for the motor to energize said operating windings and to successively interrupt the energizing circuits of said holding windings for successive operation of said switches, a device

associated with each of said holding windings and coacting therewith upon interruption of its associated energizing circuit to delay operation of its associated switch, means associated with certain of said devices for normally reducing the delaying effect thereof, said latter means being rendered ineffective upon starting of the motor.
